UNITED STATES PATENT OFFICE.

WILLARD B. FARWELL, OF NEW YORK, N. Y.

DRY-ORE CONCENTRATOR.

SPECIFICATION forming part of Letters Patent No. 257,681, dated May 9, 1882.

Application filed November 28, 1881. (No model.)

To all whom it may concern:

Be it known that I, WILLARD B. FARWELL, residing in the city and county of New York, State of New York, at present sojourning in San Francisco, State of California, have made and invented certain new and useful Improvements in Dry-Ore Concentrators; and I do hereby declare that the following is a full, clear, and exact description of the same, reference being had to the accompanying drawings.

My invention relates to ore-concentrating machines or apparatus of that class or variety in which separation of the metallic portions of pulverized ore is effected through the agency of a blast or current of air so applied to the mass or body of ore to be treated that the lighter and worthless particles are acted upon more powerfully by the blast, and are thereby blown or forced outward to the surface, while the metallic particles, by virtue of their greater specific gravity, are permitted to settle down in opposition to the blast, and thus separate themselves from the lighter particles that pass or are carried off as waste matter.

The accompanying drawings form a part of this specification and illustrate the invention.

Figure 1 is a vertical longitudinal section of the device. Fig. 2 is a plan view thereof. Fig. 3 is a vertical cross-section of Fig. 2, looking in the direction of the arrow. Figs. 4 and 5 show details enlarged. Fig. 4 shows the scraping device in position for action. Fig. 5 shows the same in the position it is made to assume during the back stroke when it is out of action.

Similar letters of reference indicate corresponding parts in all the figures.

The ore is introduced into a hopper, A, which I provide at one end of the machine in a position to deliver its contents upon the bed B, maintained in a substantially horizontal position across the top of a supporting-frame, C C, and immediately over a bellows apparatus, E E, into which a supply of air is forced to produce and direct a strong blast of air beneath and upward through the bed or ore-supporting surface. This bed B is made of suitable textile material, such as is provided with perforations or interstices to permit the passage of the air-blast. This bed or supporting surface is stationary during the general operation of the machine, and has no motion and per-

forms no part or function in the distribution and progression of the ore from the hopper; but the ore is mechanically spread upon its surface and distributed in a layer of uniform depth or thickness by a set or number of reciprocating rakes or scrapers, G G. These I construct and operate substantially in the following manner: In a rectangular frame, composed of longitudinal rails *h h* and cross strips *i i*, I fix a number of bars in horizontal transverse rows or positions at regular distances apart, and support them by pivot-bearings taking into the side rails, *h h*, so that these bars can turn freely in the frame in a similar manner to the slats of a blind. From each one of these pivoted bars a blade or scraping-edge, *g*, projects in a downward direction toward the bed B, but out of contact with the bed-surface beneath the bars, and of such width that when in the vertical or working position the edge of the scraper shall pass over the bed at a certain distance above its surface. This distance will determine the depth of the gangue or matter that is to be left upon the bed, and the quantity that is to be passed or carried off by the action of these scrapers and discharged from the end of the bed as tailings.

The frame carrying the bars G G is supported between the side frames *b b* of the machine upon rollers *d d*, and a longitudinal reciprocating motion is given to it by means of the crank-shaft J and the rod or pitman K, connecting the crank with one end of the frame. The scrapers, however, are caused to act against the matter beneath them only during the forward movement, in a direction from the hopper or receiving end toward the discharge end of the bed, for which purpose the bars G are given a slight rotation or movement on their pivots in a forward direction at the beginning of each backward movement of their carrying-frame, so that the blades or scraping-edges of the bars are turned upward into an inclined position, and held therein to pass over and clear the top of the ore-layer on the bed while the frame completes its backward or return movement. Therefore at each movement of the scrapers G in the direction away from the hoppers they engage with the upper portion of the ore body or layer to carry it forward, and at the return movement they are raised out of action. A simple and efficient means for op-

erating these scrapers is shown in Fig. 1 of the drawings, and in detail in Figs. 4 and 5, where a bar, *m*, placed along and over the center of the reciprocating frame *h i*, has each bar *G* 5 connected with it by means of an ear or short upright lug, *n*, projecting from the top of the bar *G* and pivoted in a slot in the under side of the bar *m*. At the outer end this bar *m* is then attached or connected to the lower end 10 of a short lever, *p*, pivoted at the center *q* to an upright post, *R*, fixed upon the cross-rail *i* of the scraper-frame, and having its upper end connected by a pivot-joint, *s*, to the rod or pitman of the crank. This rod in its forward 15 movement throws the lower end of the pivoted lever *p* backward, and gives sufficient movement to the bar *m* in the same direction to rotate the scraper-bars *G* upon their pivot and bring their blades or scrapers in upright position, at which time or point in the movement of the bar *m* also a stop, *T*, provided on the 20 under side of the pitman, is brought against the upright post *R*, and the remaining motion of the pitman is caused to move the frame *h i* 25 forward on the rollers *d*. At the backward or return movement of the pitman the lever *p* first receives the action of the crank, and in being turned to an upright position it throws the bar *m* forward and brings the blades or 30 scrapers *g g* into an inclined position, or out of action, after which, the further movement of the bar *m* being arrested by the contact of the lower edge of the side rails, *h h*, with the top of the bars *G G*, the frame, with the scrapers 35 *g g* in the inclined position, is then drawn back by the continued rotation of the crank. Thus at each forward movement the scrapers are first brought into the vertical position and carried forward, and then turned up at an angle, 40 or from the vertical, to pass over the surface of the ore on the bed before beginning their return movement.

By making the stop *T* adjustable toward and from the post *R*, so as to come in contact with it at a point sooner or later in the forward movement of the pitman, I can cause the bars *G G* to move forward and act against the ore before they come to the vertical and while they hold a position more or less inclined, so that 45 their penetration into the layer of ore may be increased or diminished by simply changing the position of this stop *T* to or from the post *R*.

In the operation of this machine the ore, when introduced into the hopper, is directed onto the 50 forward end of the movable perforate bed *B*, and then as the shaft *J* is rotated the set of distributing and progressing blades or scrapers *G* is set in motion by the crank *J* and the connecting-rod *K*, while at the same time the air-bellows *E E* is operated by the cranks *W W* on the same shaft to force a blast of air up through the bed. As the blades reciprocate over the bed a portion of the ore at the hopper is caught by the first blade, carried forward, 55 and spread by it over the surface, and then at the next movement of the frame this portion

comes in front of and is caught by the next blade, and thus in regular manner the portion of ore taken each time by the first blade is progressed and carried toward the tail of the machine. A layer of uniform depth is thus mechanically formed and maintained upon the bed, and at the same time the upper portion of this layer is receiving the lighter and worthless particles that are constantly being worked upward and separated from the body of the the gangue upon the bed beneath; and while these scrapers *G* are distributing the matter over the bed and carrying it along to receive the action of the air-blast they are also acting to remove the top of the layer and discharge it at the end of the machine. The heavy metallic particles in this manner gravitate toward and finally settle down upon the bed-surface. To provide for mechanically removing this lowest portion, consisting of the metallic concentrations, I construct the perforate bed *B* of a length of woven or textile material, which I connect or attach at each end to a horizontal winding drum or roller *P*, and then by mounting these rollers in bearings in the side frames *C C*, I hold and support the bed-surface *B* in proper position with and relation to the scrapers *G*, and also enable the surface to be drawn longitudinally in one direction or the other, so that by simply winding it upon one roller *P* this bed can be drawn along toward one end of the machine, and any matter deposited on it will be mechanically discharged as the surface is wound around one roller and drawn from the other.

Immediately over the bed *B*, but with their lower edges slightly elevated above it to be out of contact with it, I fix at intervals a number of cross-slats, *L L*. These are secured at the ends to the side frames *b b*, and extend transversely over the bed, forming a number of shallow receptacles, over which the scrapers travel and beneath which is supported the bed *B*. Within the recesses or receptacles thus formed the gangue rests and is confined, undisturbed by any other influence than the air-blast, having constant applications of ore spread and distributed in them by the action of the scrapers, and as regularly having the lighter particles thrown out and raised to the surface by the currents of air from below into position to be caught by the scrapers. These slats or bars *L* serve to hold and retain the gangue in place while the bed is being drawn longitudinally outward in discharging the metallic particles from the lowest portion of the layer, and their lower edges, *l*, being elevated slightly above the bed-surface *B*, a certain portion of the concentrated or separated matter therein can pass beneath them and move outward with the bed; but all the gangue above that line is confined by and held at rest within the recesses between the bars *L*.

In the construction shown in the drawings I have placed the forward winding-roller *P* within the compartment *V*, from which a spout

or discharge, *w*, conducts the ore matter as it falls from the bed-surface; and to direct the waste matter over this roller and thus separate it from the metallic portion being drawn out by the movable bed, I fix over the compartment *V* a plate or surface, *X*, about on a level with the top of the bars *L*, so that the tailings are carried over it and thrown out at the end of the machine by the action of the scrapers at the end of the set. Hand-wheels *P'* are provided on both winding-drums *P* for drawing the bed backward to bring it into position, as well as forward to clear off the concentrations. Intermediate supporting-rollers, *u u*, are introduced in front of the winding-rollers *P* for the purpose of holding the bed-surface *B* in horizontal position and keeping it properly stretched or at the required state of tension over the air-blast beneath.

In the above-described apparatus for spreading and distributing the ore it will be seen that the scrapers are constantly at work carrying forward a certain quantity of the pulverized matter, and causing it to progress regularly over the bed and be distributed laterally as it goes forward in a manner to receive the free action of the air-blast, and that the quantity taken at each time by the first scraper is advanced by the other scrapers in succession, and is thereby spread out in a thin sheet or layer in a condition to be thoroughly acted upon by the air; also, that the contact of the scraping edges or blades with and their penetration into the ore matter at the forward movement can be adjusted through the medium of the adjustable stop *T*.

Having thus fully described my invention, what I claim, and desire to secure by Letters Patent, is—

1. In an ore separating or concentrating machine, the combination of a perforate ore supporting surface, means for moving it forward or backward when desired, means for distributing the pulverized ore thereon evenly and for moving the light particles forward toward

the discharge end, and an air-blast apparatus located beneath and forcing the current of air upward through the supporting-surface and ore-stratum, as set forth.

2. The combination, in an ore-separator, of 50 the perforate ore-supporting surface *B* and means for directing upward through said surface a blast of air with the ore-spreading blades *G* and the bars *L*, as set forth.

3. In an ore-separator, the combination, with 55 a perforate ore-supporting surface, means for delivering ore thereon, and means for moving said surface in either direction, of a series of rakes, *G*, and means for imparting to them a reciprocating movement for acting upon the 60 stratum of light material in one direction and for elevating them above it in the other direction, substantially as set forth.

4. The combination of the reciprocating frame *h i*, and supporting-surface *B* with the pivoted bars *G*, provided with blades *g*, mechanism for giving said frame a longitudinal reciprocating motion, and means for turning said bars upon their pivots to bring the blades thereof into an inclined or angular position during the reciprocation of their carrying-frame in one direction and for turning them down into vertical or working position at the return movement of the said frame, substantially as hereinbefore described, for the purpose set forth. 75

5. The combination, in a dry-ore separator, of the longitudinally-movable perforate supporting-surface *B*, the transverse slats *L*, the longitudinally-reciprocating scrapers *g g*, and the air-blast mechanism *E E*, substantially as 80 hereinbefore described.

6. The reciprocating frame *h i*, having scrapers *G*, the bar *m*, connections *n*, the lever *p*, post *R*, the pitman, the crank, and the stop *T*, all combined to operate substantially as set 85 forth.

WILLARD B. FARWELL.
